Primary Examiner — Michelle E. Wilson*Assistant Examiner* — Celse Moore, Jr.(74) *Attorney, Agent, or Firm* — Jeffer Mangels Butler & Mitchell LLP; Brennan C. Swain, Esq.(57) **CLAIM**

The ornamental design for shorts, as shown and described.

DESCRIPTION

FIG. 1 is a perspective view of a pair of Shorts, showing our new design;

FIG. 2 is a front elevational view thereof;

FIG. 3 is a rear elevational view thereof;

FIG. 4 is a right side elevational view, with the left side elevational view being a mirror image thereof; and,

FIG. 5 is a front elevational view of the present invention, with a portion of the front of the shorts cut away and a portion of inner layer of the back cut away.

The shading shown in the drawings is for illustrative purposes only and forms no part of the claimed design.

The broken lines shown in the figures are for the purpose of illustrating portions of the present invention that form no part of the claimed design.
